UNITED STATES PATENT OFFICE.

GEORGE W. KELLOGG, OF ROCHESTER, NEW YORK, ASSIGNOR TO KELLOGG MFG. CO., OF ROCHESTER, NEW YORK, A CORPORATION OF NEW YORK.

PUMP.

1,181,318.

Specification of Letters Patent.

Patented May 2, 1916.

Application filed February 12, 1914. Serial No. 818,185.

To all whom it may concern:

Be it known that I, GEORGE W. KELLOGG, of Rochester, in the county of Monroe and State of New York, have invented certain new and useful Improvements in Pumps; and I do hereby declare the following to be a full, clear, and exact description of the same, reference being had to the accompanying drawings, and to the reference-numerals 10 marked thereon.

My present invention has for its object to provide a pump adapted particularly to be used for compressing air or other gases in which the parts are so arranged that excessive heating of the piston is obviated and the parts are kept thoroughly lubricated without the liability of the oil, or other lubricating substance, being carried into the pressure line of pipe.

20 To these and other ends the invention consists in certain improvements and combinations of parts, all as will be hereinafter more fully described, the novel features being pointed out in the claims at the end of 25 the specification.

In the drawings: Figure 1 is a side elevation of a pump constructed in accordance with my invention; Fig. 2 is a vertical sectional view thereof; Fig. 3 is a horizontal 30 sectional view taken on the line 3^x—3^x of Fig. 2, and Fig. 4 is a detail view showing in section the upper end of the pump cylinder, the inclosed piston and the cylinder head coöperating therewith.

35 Similar reference numerals throughout the several figures indicate the same parts.

The pump illustrated as showing one embodiment of my invention comprises a shell or cylinder having a main or body portion 40 1, of given diameter, and the end portion 2 of greater diameter interiorly to form an annular chamber 3 which is open to the atmosphere through a plurality of apertures 4 circumferentially disposed in the wall of 45 the cylinder and preferably located at the point of juncture between said body 1 and enlarged end 2. The cylinder walls are further provided with a plurality of conduits or channels, two of which are shown 50 in the present instance, indicated by 5, which

serve to connect the two ends of the cylinder and form conduits through which any excess of lubricating oil which may accumulate in the bottom of the chamber 3, by reason of the reciprocation of the piston, 55 may easily return to the bottom of the cylinder. The latter is closed at its lower end by a crank case 6 secured in position by the bolts 7 and between these parts and journaled in suitable bearings 8 is the crank 60 shaft 9, connected by the pitman 10 to the journal pin 11 of the piston 12. The piston 12 is provided on its outer end with an annular rim 13, the parts of the pump being so designed that while the piston 12 reciprocates in and is guided by the body 1 of the cylinder, the upper edge of its rim 13, projects above the end of said body and reciprocates in the chamber 3, so that its outer surface is always exposed to the air thereby 70 permitting the rapid dissipation of any heat developed by reason of friction between the parts. A further and equally important advantage is obtained by the enlarging of the upper end of the cylinder and the 75 designing of the parts so that the upper edge of the rim of the piston is not retracted into the body 1 of the cylinder as the lubricating oil is thus prevented from working its way upward upon the exterior surface of the 80 piston and into the recess within the latter.

The cylinder head 14 is located within the cylinder and is supported on the inwardly projecting tubular post 14^a depending centrally from the flange or cap 15, which is 85 seated in an annular notch 16, formed in the edge of the enlarged portion 2 of the cylinder and in which it is securely locked by the flange 17 of a screw-threaded ring 18. As shown, the head 14 coöperates with the 90 inner surface of the flange 13 of the piston and is provided with one or more packing rings 19. It should also be stated that the supporting of the cylinder head centrally, as shown in Fig. 2, permits the inner surface of the rim of the piston to be exposed to the cooling influence of the air in the cylinder chamber 3, thus assisting in preventing the parts from becoming over-heated.

Inlet and outlet valves are provided for controlling the admission of air or gas into the compression space between the piston 12 and the cylinder head and I deem the preferred arrangement of these parts to be that shown in Figs. 2 and 3. In these illustrations the inlet valve is indicated as comprising a head 20 carried on a stem 21, guided in a spider 22, located in the inlet aperture in the bottom of the cylinder head. The valve is normally held in closed position by a spring 23 which rests upon and also serves as a means of holding in place a gauze screen 24. The outlet valve comprises a ball 25 resting upon a seat 26 at the bottom of the port 14^a containing the spring 28 which is held in place by a screw cap 29 from which leads the pressure conduit pipe, indicated by 30.

A pump constructed in accordance with my invention is capable of use for a variety of purposes and is particularly adapted to be used as an air pump arranged to be driven by the engine of an automobile for supplying air under pressure for any purpose for which it may be desired. The construction of the parts of the pump permit it to be driven at high speed and to compress air under high pressures without becoming heated. The arrangement of the cylinder head within the recessed piston and the provision for lubricating the latter exteriorly and preventing the lubricating substance from working its way into the compression chamber obviates the inconveniences and disadvantages occasioned by the presence of oil in the pressure line and which becomes a serious menace if the oil used is of a mineral base and any considerable quantity is forced into the tires of an automobile.

I claim as my invention:

1. In a pump, the combination with a cylinder having a body portion of given diameter and an end portion of greater diameter, apertures formed through the wall of the cylinder for admitting air thereto, an inwardly extending head disposed in spaced relation to the side and end walls of the cylinder, the outer face of the head being directly exposed to air admitted to the cylinder through said apertures, a piston guided in the body of the cylinder and having an annular rim movable in the larger portion of the cylinder in spaced relation to the walls thereof, said rim being in engagement with the aforementioned head, the outer surface of the rim being directly exposed to the air admitted through said apertures, and inlet and outlet valves arranged on the head.

2. In a pump, the combination with a cylinder having a body portion of given diameter and an end portion of greater diameter,

apertures formed through the wall of the cylinder for admitting air thereto, an inwardly extending head mounted on the cylinder disposed in spaced relation to the side and end walls thereof, the outer face of the inwardly extending head being directly exposed to air admitted to the cylinder through said apertures, a piston guided in the body of the cylinder and having an annular rim movable in the larger portion of the cylinder in spaced relation to the walls thereof, said rim being in engagement with the aforementioned inwardly extending head, the inner and outer surfaces of the rim being directly exposed to air admitted through said apertures, and inlet and outlet valves arranged on the head.

3. In a pump, the combination with a cylinder having an enlarged upper end provided with apertures for admitting air thereto and a crank case at its lower end, channels connecting its enlarged upper end with the crank case, an inwardly extending head mounted on the cylinder disposed in spaced relation to the side and end walls thereof, the outer face of the inwardly extending head being directly exposed to air admitted to the cylinder through said apertures, a piston guided in the body of the cylinder and having an annular rim movable in the larger portion of the cylinder in spaced relation to the walls thereof, said rim surrounding the aforementioned inwardly extending head, the inner and outer surfaces of the rim being exposed to air admitted through said apertures, and inlet and outlet valves arranged on the head.

4. In a pump, the combination with a cylinder having an enlarged upper end provided with apertures and a crank case at its lower end, said cylinder having channels connecting its enlarged upper end with the crank case, of a piston guided in the cylinder having an end rim projecting into said enlargement of the cylinder and a head on the latter projecting into the cylinder and a packing ring on the head coöperating with the inner wall of the rim of the piston and inlet and outlet valves carried on said head.

5. In a pump, the combination with a cylinder having a body of given diameter and an end portion of greater diameter which is open to the atmosphere, of a piston guided in the body of the cylinder and having a rim moving into and out of the enlarged end of the cylinder, a cylinder head engaging with in the rim of the piston and a post supporting it of less diameter than the head and having means for attachment engaging the cylinder.

6. In a pump, the combination with a cylinder having a body of given diameter and an end portion of greater diameter which is open to the atmosphere, of a piston guided

in the body of the cylinder and having a rim moving into and out of the enlarged end of the cylinder, a cap secured to the end of the cylinder having a central tubular post extending into the cylinder, a head carried by the post and coöperating with the inner surface of the piston rim, an inlet

valve in said head and an outlet valve located in the perforation of said post.
